(57) **CLAIM**

The ornamental design for a user interface for a portion of a display screen, as shown and described.

DESCRIPTION

The FIGURE is a front view of a user interface for a portion of a display screen showing my new design.

The broken line showing of various regions and the unshaded areas there within form no part of the claimed design. The broken line showing the display screen is for illustrative purposes only and forms no part of the claimed design.

1 Claim, 1 Drawing Sheet
